UNITED STATES PATENT OFFICE.

WILLIAM C. TEMPLE, OF PITTSBURG, PENNSYLVANIA.

STEAM-BOILER.

SPECIFICATION forming part of Letters Patent No. 613,332, dated November 1, 1898.

Application filed October 28, 1897. Serial No. 656,654. (No model.)

To all whom it may concern:

Be it known that I, WILLIAM C. TEMPLE, of Pittsburgh, in the county of Allegheny and State of Pennsylvania, have invented a new and useful Improvement in Steam-Boilers; and I do hereby declare the following to be a full, clear, and exact description of the same, reference being had to the accompanying drawings, in which—

10 Figure 1 is a vertical central section of my improved boiler, and Fig. 2 is a horizontal section on the lines II II of Fig. 1.

My invention relates to improvements in steam-boilers, particularly of that class to 15 which belongs the Cahall boiler, shown in Patent No. 485,088, granted to John Cahall on October 25, 1892.

The object of my invention is principally, first, to provide for the easy removal of soot, 20 ashes, and other foreign matters that deposit upon the tube-sheet of the mud-drum in this class of boiler, and, secondly, to so arrange the exterior shell in its relation to the metal portion of the boiler as to allow free expansion of the latter and at the same time to 25 render the construction practically tight against the admission of outside cold air into the smoke-flue or into contact with the heating-surfaces.

30 My improved boiler has a combustion-chamber and an annular mud-drum, beneath which is a pit or chamber for the accumulation of foreign substances which may from time to time deposit on the tube-sheet of the 35 mud-drum and which are blown or forced thence through the central vertical space in the mud-drum down into the chamber beneath.

In the drawings, 2 designates the external 40 masonry shell of the boiler. 3 is an annular steam-drum arranged within said shell, near or at the upper end thereof, and connected by a concentric bank of water-tubes 5 with an annular mud-drum 4, arranged at or near the 45 lower portion of the shell. The annular steam-drum 3 is provided with a central vertical flue 6, opening into a stack 6'. The annular drum 4 has a vertical opening 7, which communicates at its lower end with a pit 8 and 50 at its upper end communicates with the central vertical space 9, which is within the bank of tubes and which connects at its upper end

with the central opening through the steam-drum.

10 is the combustion-chamber, which dis- 55 charges its gases and products of combustion laterally among the tubes above the mud-drum. 11 11 are deflectors, one or more in number, arranged to retard the passage of these gases in their vertical travel through 60 the boiler. The opening 7 in the mud-drum is not a flue for the passage of the products of combustion, for these enter the heating-space of the boiler not through the said opening, but above the same. 65

The boiler is supported by the mud-drum, which rests upon or is upheld by the foundation of the masonry structure. Between the steam-drum and the external wall or shell 2 I place a packing-ring 12, of asbestos rope or other suitable material, which serves to close the space between the drum and the shell and yet is elastic and yielding enough to permit the rise and fall of the whole boiler structure, due to its natural expansion 70 and contraction, without binding or straining the shell. 75

By the construction above described I provide simple and effective means for relieving strains upon the shell incasing the boiler, 80 which might be occasioned if the shell were in contact with the upper portion of the boiler, at which portion the results of such contraction and expansion are the greatest, and I effect this result without in any way 85 injuring or lowering the efficiency of the boiler or affording any space for the admission of cold air into contact with the steam-spaces, and I moreover provide for the easy and ready removal of foreign matter, which 90 will fall from the tube-sheet of the mud-drum into the pit 8. A further advantage appertaining to the annular construction of the steam-drum and mud-drum is that these drums are rendered very strong and capable 95 of resisting great strains without the necessity for using special internal braces.

I claim—

1. A vertical water-tube boiler having an annular steam and mud drums, a connecting 100 vertical bank of tubes, and a combustion-chamber discharging its gases and products of combustion laterally among the tubes above the mud-drum, the course of the gases

being upwardly and not through the mud-drum, substantially as described.

2. A vertical boiler having an exterior shell, an annular mud-drum arranged at the lower 5 part of said shell, a steam-drum at the top part of the exterior shell provided with a central vertical smoke-flue which communicates with the stack of the boiler, a concentric bank 10 of water-tubes connecting the steam-drum and mud-drum, a combustion-chamber discharging its gases and products of combustion laterally among the tubes above the mud-drum, the course of the gases being upwardly 15 and not through the mud-drum, and one or more deflectors arranged within the central vertical space, between the tubes, substantially as described.

3. A boiler having an exterior shell, a mud-drum, a steam-drum arranged within and at 20 the upper part of the exterior shell but not

in contact therewith, a surrounding packing of yielding material adapted to close the space between the steam-drum and the exterior shell and to permit vertical motion of the steam-drum, and a support below the steam-drum for supporting the boiler, substantially 25 as described.

4. A vertical water-tube boiler having a bank of tubes, an annular mud-drum, and a combustion-chamber discharging its gases 30 and products of combustion laterally among the tubes above the mud-drum the course of the gases being upwardly and not through the mud-drum; substantially as described.

In testimony whereof I have hereunto set 35 my hand.

W. C. TEMPLE.
